UNITED STATES PATENT OFFICE

146,805

DESIGN FOR A CARD AND POKER CHIP RACK

Eugene K. Millhauser, Los Angeles, Calif., assignor to Martin Oedekerk, Jr., Los Angeles, Calif.

Application December 3, 1945, Serial No. 124,292

Term of patent 3½ years

(Cl. D34—5)

To all whom it may concern:

Be it known that I, Eugene K. Millhauser, a citizen of the United States, residing in Los Angeles, in the county of Los Angeles and State of California, have invented a new, original, and ornamental Design for a Card and Poker Chip Rack, of which the following is a specification, reference being had to the accompanying drawing, forming a part thereof.

Fig. 1 is a front elevation showing my design for a card and poker chip rack.

Fig. 2 is a perspective view.

Fig. 3 is an end elevation.

I claim:

The ornamental design for a card and poker chip rack, as shown.

EUGENE K. MILLHAUSER.
